UNITED STATES PATENT OFFICE.

LEANDER EWING, OF CORNING, ARKANSAS.

IMPROVEMENT IN COTTON-SCRAPERS.

Specification forming part of Letters Patent No. 174,507, dated March 7, 1876; application filed August 7, 1875.

To all whom it may concern:

Be it known that I, LEANDER EWING, of Corning, in the county of Clayton and State of Arkansas, have invented a new and valuable Improvement in Cotton-Scrapers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side view of my cotton-scaper, and Fig. 2 is a plan view of the same. Fig. 3 is a sectional detail view, and Fig. 4 is a longitudinal vertical sectional view.

This invention has relation to improvements in cotton-scrapers, the object of which is to chop the surplus plant out of a drill, and to clear the incline of the drill or ridge of grass, weeds, and other unnecessary growths.

The nature of the invention consists in the combination, with a rotary cutter mounted in a suitable frame, and having the end of its shaft provided with a crank-arm, of a coiled spring attached to the end of the said crank and to the frame of the rotary cutter, whereby the said cutter will be held up out of the way when its operating-shaft is thrown out of gear with a master-wheel. It also consists in the combination and arrangement of the parts, as will be hereinafter more fully set forth.

In the annexed drawings, A designates the beam of my improved scraper, which is provided upon its right front side and end with a rectangular frame, B, which affords a bearing for the journals of the shaft *a* of a master-wheel, C. This wheel is, preferably, of wood, and it may be provided with a tire. It has also free lateral movements in its bearings, one of which is in frame B, and the other in the beam A, and is provided with a rack-wheel, D, upon the side next the beam, which engages with a pinion, *c*, upon the front end of a rotating shaft, E, which has its bearings in a hanger, *d*, depending from the beam, and in a rectangular guard-frame, F, which is rigidly secured to the extreme rear end of the beam, with its open end downward, as shown in Fig. 1. G represents a U-shaped cutter, which is secured upon shaft E, where it passes

through guard-frame F, and is actuated through shaft E and pinion *c* by the rotation of master-wheel C as the machine is drawn over the ground. Wheel C is held to its engagement with pinion *c* by means of a spring, *s*, which is applied on shaft *a* between the said wheel and its outer bearing in frame B, and is suitably compressed between the same. When it is not desirable to operate the cutter, wheel C is thrown out of gear with pinion *c* by means of a lever, H, which is pivoted at *e* to the beam, and extends rearwardly to within convenient reach of the operator holding the plow-handles I I', passes from its fulcrum along the beam, is bent downward outside the same, and is connected loosely with the projecting end of the journal of shaft *a*. This lever, when thrust to the left, will throw the rack-wheel and pinion out of engagement, and when engaged with a catch, *f*, upon the round *g* bracing the handles I I', will hold them in this position. In order to hold rotary cutter G out of the way of casual injury when not in use, the end of its shaft E is provided with a crank-arm, *h*, to which a spring, *S*, of suitable strength is attached, the other end of the said spring being attached to the guard-frame F, as shown in Fig. 1. This spring, by its reaction, will give shaft E a semi-rotation, swinging its cutter up into its guard F. Beam A, before alluded to, is provided with a scraper-standard, J, upon the lower beveled end of which is pivoted a metallic scraper, K, which is guided in its vibrations by means of a bolt passing through a curved slot cut in the scraper into the standard. This scraper is adjusted to suit a flat or sharp ridge by means of a metallic rod, L, attached to the upper end of the said scraper, and passing up through a metallic plate, *k*, rigidly secured in a horizontal position to beam A, and the adjustment thus obtained is maintained by means of nuts *n* applied upon the screw-threaded upper end of the said rod, the one above and the other below plate *k*. The beam M of the cultivator-teeth standards N is formed of a single piece of timber bent into the form shown in Fig. 2, and mortised into the beam A of the scraper. It is thus endowed with great strength, the grain of the wood not being broken, and may be made

very light in comparison with others now in use.

In order to regulate the penetration of the cultivator-teeth *l* and of the scraper into the ground, I propose to employ a small wheel, *P*, rotating in bearings in the lower end of a metallic rod, *O*, which passes upward through beam *M*, with its screw-threaded upper end engaged in a nut, *o*, of circular form, which is held in position by being inclosed in a metallic box, *p*, rigidly secured in any suitable manner upon the upper surface of beam *M*. This nut is caused to rotate for raising or lowering wheel *P* by means of an operating handle, *Q*, in the nature of a crank-arm, which handle is rigidly secured to the nut, and is allowed to rotate freely in a circular aperture in the nut-box, as shown in Fig. 2; and in this manner a very effectual means for regulating the penetration of the scraper and cultivator-teeth is obtained. The front end of frame *B* is flattened, and is provided with a number of spaced perforations *i* by means of

which it is adapted to serve as a clevis, a ring, *r*, being placed in one of these perforations to receive a hook on the single-tree.

What I claim as new, and desire to secure by Letters Patent, is—

1. In a cotton-scraper, the spring *S*, in combination with rotating cutter-bearing shaft *E*, having crank-arm *h*, substantially as specified.

2. The laterally-movable master-wheel *C* and spring *s*, in combination with the rotating cutter-bearing shaft *E*, having pinion *e*, substantially as specified.

3. The vibrating lever *H*, in combination with a laterally-movable master-wheel *C*, shaft *E*, and pinion *e*, substantially as specified.

In testimony that I claim the above I have hereunto subscribed my name in the presence of two witnesses.

LEANDER EWING.
